UNITED STATES PATENT OFFICE.

ROBERT HENKE, JR., OF NEW YORK, N. Y.

GOLD-LEAF BOOK.

No. 820,717.

Specification of Letters Patent.

Patented May 15, 1906.

Application filed January 25, 1906. Serial No. 297,867.

To all whom it may concern:

Be it known that I, ROBERT HENKE, Jr., a citizen of the United States, residing at New York city, Manhattan, county and State of New York, have invented new and useful Improvements in Gold-Leaf Books, of which the following is a specification.

This invention relates to improved means of securing gold leaves to the sheets of a tissue-paper book in a quick, simple, and effective manner.

In the accompanying drawings, Figure 1 is a perspective view of a gold-leaf book constructed according to my invention. Fig. 2 represents one side of one of the book-leaves. Fig. 3 represents the reverse side of said leaf, and Fig. 4 is a diagrammatic section illustrating the method of making the book.

My improved gold-leaf book consists of a number of sheets or leaves of tissue-paper *a*, bound at the back, as at *a'*, to form a book, Fig. 1. To one side of each sheet *a* is secured by pressure the gold-leaf *b*, Fig. 2. To the opposite side of sheet *a* is secured a non-adhesive ocher powder *c*, Fig. 3. In this way the gold-leaf *b* on one sheet is faced by the powdered side *c* of the next sheet, which prevents the gold-leaf from adhering to such sheet.

In carrying out my invention I proceed as follows: I first bind a number of sheets *d* of tissue-paper into a book. I then interpose

between each two sheets *d* a gold-leaf *e* and a transfer-sheet of ocher paper *f*, Fig. 4, powdered on both sides. The book thus charged is subjected to the action of a press, the pressure serving to attach the gold-leaf to one side of the tissue-paper and also to transfer some of the ocher powder from the back of the transfer-sheet to the opposite sheet of tissue-paper. As the front of the transfer-sheet is also powdered, the pressure will, however, not cause the gold-leaf to become attached to the transfer-sheet. After the pressure has been applied for a short time the book is taken out of the press and the transfer-sheets are removed.

What I claim is—

The method of making a gold-leaf book which consists in binding a number of leaves of tissue-paper into a book, interposing a gold-leaf and a sheet of transfer-paper powdered on both sides between each pair of tissue-leaves, subjecting the book to pressure, and then removing the transfer-sheets, substantially as specified.

Signed by me at New York city, (Manhattan,) New York, this 24th day of January, 1906.

ROBERT HENKE, JR.
